(57) **CLAIM**

The ornamental design for an air pressure massager controller, as shown and described.

DESCRIPTION

FIG. 1 is a front perspective view of the air pressure massager controller showing my new design;

FIG. 2 is a front elevational view thereof;

FIG. 3 is a back elevational view thereof;

FIG. 4 is a right elevational view thereof;

FIG. 5 is a left elevational view thereof;

FIG. 6 is a top plan view thereof; and,

FIG. 7 is a bottom plan view thereof.

The Broken lines shown in the figures are for the purpose of illustrating portions of the air pressure massage controller, which form no part of the claimed design.
